WALLPAPER MARKING MACHINE

Edwin N. Burrows, Royal Oak, Mich.

Application April 8, 1937, Serial No. 135,643

3 Claims. (Cl. 33—189)

The present invention relates to apparatus for marking wallpaper in such manner that the same may be cut to length after the border which bears the pattern indicating marks has been trimmed off.

Wallpaper usually has a border at each edge thereof bearing marks which indicate the pattern limits so that by cutting the paper in line with these marks placement of several strips so cut 10 on a wall, with the upper end of the several strips in a straight line, causes the pattern of the several strips to match. These marks which indicate the pattern and which are usually placed on a border provided at each side of the wall- 15 paper are removed when the borders are trimmed off, as must be done prior to placing the paper on the wall, with the result that no indication is left other than the pattern itself to permit matching of the pattern of one strip with the 20 pattern of the next adjacent strip. Therefore, in order to permit matching of the patterns of adjacent strips it is necessary to cut the strips to length before the borders are trimmed therefrom.

The principal object of the present invention 25 is to provide apparatus whereby rolls of wallpaper may be trimmed and marked on the sides opposite to that bearing the pattern in order that when the wallpaper is placed upside down on a table for the purpose of receiving an application 30 of adhesive it may be cut to length. In other words, this invention aims to provide wallpaper with pattern indicating marks on the rear face thereof at the points where it should be cut in order that by placing adjacent strips on a wall 35 with their upper ends in line matching of the patterns on adjacent strips automatically results.

With the above and other ends in view the invention consists in matters hereinafter more particularly set forth with reference to the accompanying drawings in which

Figure 1 is a plan view;

Fig. 2 is a front elevation partly in section;

Fig. 3 is a vertical transverse section;

Fig. 4 is an elevation of a measuring device;

Fig. 5 is a vertical transverse section thereof, and

Fig. 6 is a perspective of a strip of paper.

Like characters of reference are employed throughout to designate corresponding parts.

The numeral 1 designates a machine frame having a table 2 at the top thereof and a pair of rollers 3 and 4 at opposite sides of the table. The roller 3 is adapted to have a roll 5 of wallpaper placed thereon and the roller 4 is connected by a 55 sprocket and chain arrangement 6 to a shaft 7

carrying cutters 8. The shaft 7 is adapted to be rotated through means of a hand crank 9 or may be power driven through the pulley 10 from any suitable power source. The cutters 8 cooperate with the lower set of cutters 11 so that when the paper is unrolled from the roller 3 on to the roller 4 the border is trimmed therefrom. This mechanism above described represents a conventional wallpaper trimmer.

The table 2 is provided with a slot 12 which extends transversely with respect to the direction of movement of the paper thereon. Mounted beneath the slot 12 is an ink pad 13 with a cam surface 14 adjacent one end thereof. A rod 15 is slidably mounted beneath the table and has a marking disk 16 supported on its inner end by a flexible element 17. When the rod 15 is manually moved toward the right hand side of Fig. 2 the marking disk is moved up the cam surface 14 and across the ink pad 13. The cam surface 14 elevates the marking disk to a plane where it engages the underside of the paper extending across the table 2 and the pad 13 maintains this contact and inks the disk edge so that an ink mark is placed on the underside of the paper with each operation of the rod 15.

Mounted upon the shaft housing 18 is a housing 19 having a disk 20 which contacts with the paper as it is drawn over the table 2 so that it is caused to rotate thereby. Externally of the 30 housing 19 is provided a pointer 21, the pointer being frictionally connected to a shaft 22 which is geared to the disk 20 through means of the gear train 23. Adjacent the pointer 21 graduations 24 are provided, the graduations preferably being in foot units. The pointer 21 may be moved manually relative to the shaft 22 to a position where it engages a pin 25 which defines the zero adjustment thereof, and such movement of the pointer may take place without disturbing 40 the gear train 23 or the disk 20.

In Fig. 6 there is shown a strip 26 of wallpaper having the usual border 27 at each side thereof. The surface 28 between the border is that which bears the ornamental pattern and the marks 29 on the border represent the pattern limits. If the paper strip is cut transversely in line with one of the marks 29 to form it into a plurality of strips, and such strips are placed upon a wall with their upper edges in horizontal alignment, 50 the patterns on the adjacent strips will match. The purpose of the present invention is to provide a mark 30 on the surface of the strip 26 opposite to that which bears the pattern in order that the borders 27 may be trimmed therefrom 55

and the paper cut to length after the strip is trimmed. This is accomplished by rotating the roller 4 to unwind the paper roll 5 from the roller 3 and wind the same upon the roller 4, there-
5 by causing the paper to move over the table 2 and the disk 20, being in contact therewith, is caused to rotate and operate the pointer 21. When the pointer 21 indicates that a required length of paper has passed over the table the
10 roller 4 is stopped. If at the time the roller 4 is stopped one of the marks 29 is opposite the pointer 31, the rod 15 is pulled outwardly manually to actuate the marking disk and apply a mark 30 to the bottom face of the paper. If at
15 the time the roller 4 is stopped the pointer 31 is not in accurate alinement with one of the marks 29, the roller 4 is actuated by the crank 9 to move the paper an additional amount until the next mark 29 coincides with the pointer 31. The rod
20 12 is then actuated to cause a mark 30 to be ap-
plied to the rear face of the strip. Prior to the winding of the paper upon the roller 4 the borders
25 are trimmed therefrom and the roll of paper
which is formed upon the roller 4 is removed
therefrom and transferred to a table where it
is placed upside down for the reception of the
usual adhesive. As the paper is drawn over this
30 table it is cut at each of the marks 30 and the
adhesive is applied thereto. The patterns on
the strips so formed register when the strips are
hung adjacent to one another with their upper
edges and in horizontal alinement.

Although a specific embodiment of the invention has been illustrated and described it will be
35 understood that various changes may be made within the scope of the appended claims without departing from the spirit of the invention and such changes are contemplated.

What I claim is:

1. In a machine of the character described, a table over which a strip of paper is moved and having a recess in the top thereof, an indicator for indicating length of paper passing over said table, a roller for actuating said indicator and rotated by movement of the paper, an ink pad mounted in said recess below the top of the table, an operating member within said recess below the top of the table and movable transverse of 10 the paper, and a roller marker within said recess to engage said pad and mark the paper upon transverse movement of said operating member.

2. In a machine of the character described, a table over which strip paper passes unwinding 15 from one roll onto another, said table having a recess in the top thereof, a marker pad disposed in said recess and having an upper cam surface, a marker roller arranged to ride on said cam surface within said recess and upon movement 20 in one direction rising to mark the underside of the paper, manually operable means movable transversely of the paper to move said roller.

3. In a machine of the character described, a table over which strip paper passes unwinding 25 from one roll onto a driven roll, means for driving said driven roll, means for supporting said driving means and mounted on said table, an indicator mounted on said supporting means and operable to indicate length of paper passing over 30 said table, an actuating roller for the indicator and engaging and rotated by movement of the paper, said roller being mounted on said supporting means, said table having a recess in the top thereof, and a manually operable marking device in said recess and operable to mark the underside of the paper.

EDWIN N. BURROWS.
